UNITED STATES PATENT OFFICE

FRANK E. McCABE, OF CLEVELAND, OHIO, ASSIGNOR TO THE GRABLER MANUFACTURING COMPANY, OF CLEVELAND, OHIO, A CORPORATION OF OHIO

MOLD FLASK

Original application filed September 19, 1925, Serial No. 57,333. Divided and this application filed March 25, 1927. Serial No. 178,251.

This invention relates to an improved mold flask. While many of its novel features make the flask desirable for use in ordinary foundry practice, it is, on the other hand, peculiarly suited for use in the molding system disclosed in my former application Serial No. 57,333, filed September 19, 1925, and whereof the present case is a division. The flask is especially designed for cooperation with the molding machines and mold shake-out apparatus involved in said system. A molding machine of the character in question constitutes the subject matter of my application Serial No. 733,364, filed August 21, 1924, while the shake-out apparatus to which reference is made is disclosed in my first mentioned application, and in a division thereof filed concurrently herewith.

The purpose of my present invention is to provide a very substantial and rigid mold flask, preferably comprised of an integral casting, that is light of weight and especially suited for use in molding systems of the class referred to, and in conjunction with molding machines and shake-out apparatus of the kinds mentioned.

To the ends in view I preferably cast the frame of the flask with as thin walls as practicable, and I reinforce the walls with strengthening ribs, using by preference two ribs that are vertically spaced apart along the longitudinal sides of the frame and connect them together at their outer edges for parts of their lengths with webs, thus effecting a tubular construction that is exceedingly strong and at the same time light; and the end walls are strengthened by suitable rib arrangements which carry positioning means for properly aligning one flask with another when the flasks are stacked, and which incorporate supporting parts for cooperation with mold sustaining elements of the molding machine and shake-out apparatus.

In the accompanying drawing, Fig. 1 is a plan view and Fig. 2 a side elevation of my improved flask; and Fig. 3 shows two of the flasks in end elevation and arranged one upon the other to illustrate the manner of stacking

the flask comprises a rectangular frame 1 which is stiffened along each side by top and bottom flanges 2 and 3 that are connected together intermediate their ends by a web 4. This effects a sort of tubular formation for the longer sides of the flask which, while being light, is very strong. The importance of keeping the flask as light as practicable will be appreciated when it is explained that the flasks have to be handled manually in placing them within and removing them from the molding machines, and that several flasks at a time, stacked one upon another, have to be transported by a single carrier to the various stations of the molding system, and held suspended in similar arrangement by the shake-out apparatus.

The end walls 5 are strengthened by transverse flanges 6 which divide at their centers into top and bottom branches 7 and 8, respectively, the former being provided with dowel pins 9 and the latter with openings that are lined with bushings 10 designed to receive the dowel pins of the flask below when the flasks are stacked one upon another, as illustrated in Fig. 3. The flanges 6 preferably extend about the corners of the frame 1 to strengthen the frame in these regions.

Near the corners of the frame each flange 6 is reinforced or braced by brackets 11, and on its lower side is skirted adjacent each end by beads 12. Walls 13 which extend downwardly from the opposite end portions of each of the flanges 6 converge inwardly for a purpose that I shall presently explain. The undersides of the flanges 6 where they are partially surrounded by the beads 12 and walls 13 may be referred to as sockets 14; and it may be explained that within these sockets are adapted to engage the flask sustaining elements or arms of the molding machine, and the lifting forks of the shake-out apparatus, the latter being guided into entering relation to the sockets by means of the inwardly converging walls 13.

From the foregoing it will be seen that my invention provides a relatively light and a very strong and rigid mold flask that is especially suited for use with molding machines and shake-out apparatus of the char-

acter referred to; and attention is further called to the fact that the upper edges of the walls of the frame 1 are relatively narrow so as to avoid the lodging of sand thereon and the presence of which would of course interfere with a proper engagement of the flasks when they are stacked one upon another, and the bosses which support the dowel pins are preferably below the plane 5 of the upper edge of the flask so as to prevent any sand accumulating thereon from interfering with the correct relative positioning of superposed flasks.

Having thus described my invention, what 15 I claim is:—

1. A mold flask comprising a frame, flanges spaced apart and extending along each side member of the frame, and webs connecting the outer edges of the flanges of each side 20 member thereby to effect a tubular construction for each side member of the frame, the end members of said frame having flanges separating into upper and lower branches adjacent the transverse center thereof.

25 2. A mold flask consisting of an integral casting in the form of a rectangular frame, flanges spaced apart and extending along each side member of the frame, and webs connecting the outer edges of the flanges of each 30 side member intermediate the ends of said flanges, the ends of said frame having flanges thereon separating into upper and lower branches adjacent the transverse center thereof, said side flanges and end flanges being in 35 different planes.

3. A mold flask comprising a frame, flanges extending from the end members of the frame, the flanges adjacent the transverse center of the frame separating into upper and lower 40 branches, and dowel pins carried by the upper branches, the lower branches having dowel pin receiving apertures in axial alignment with the dowel pins, the flanges having 45 downwardly facing sockets adjacent their opposite ends, as and for the purpose specified.

4. A mold flask comprising a frame, flanges extending across the ends of the frame and around the corners thereof, the flanges adjacent the transverse center of the frame separating into upper and lower branches, and dowel pins carried by the upper branches, the lower branches having dowel pin receiving apertures in axial alignment with the dowel pins.

5. A mold flask comprising a frame, flanges spaced apart and extending along each side member of the frame, and flanges extending across the ends and around the corners of the frame between the planes of the first mentioned flanges.

6. A mold flask consisting of a rectangular frame, flanges spaced apart and extending along each side member of the frame, webs connecting the outer edges of the flanges of each side member intermediate their ends,

and flanges extending across the ends and around the corners of the frame between the planes of the former flanges.

7. A mold flask comprising a frame, flanges extending from the end members of the frame and provided at their ends with downwardly facing sockets, and inwardly converging guide walls adjacent said sockets, as and for the purpose specified.

8. A mold flask consisting of a frame having downwardly opening sockets at its ends for the reception of mold sustaining means, and guide walls adjacent said sockets for directing said means into the sockets.

9. A mold flask comprising a frame, flanges spaced apart and extending along each side member of the frame, and flanges extending across the ends and around the corners of the frame, and separating into upper and lower branches adjacent the transverse center of said frame.

10. A mold flask comprising a frame, flanges spaced apart and extending along each side of said frame, webs connecting the outer edges of said side flanges of each side member thereby to effect a tubular construction, flanges extending across the ends and around the corners of said frame and separating into upper and lower branches adjacent the transverse center thereof.

11. A mold flask consisting of an integral casting in the form of a rectangular frame, flanges spaced apart and extending along each side member of said frame, webs connecting the outer edges of the flanges of each side member intermediate the ends thereof, the ends of said frame having flanges thereon separating into upper and lower branches adjacent the transverse center thereof, the said end flanges extending around the corners of said frame.

12. A mold flask consisting of an integral casting in the form of a rectangular frame, flanges spaced apart extending along each side member of the frame, webs connecting the outer edges of the flanges of each side member intermediate the ends thereof, flanges extending across the ends and around the corners of said frame and disposed in a different plane from said first mentioned flanges.

13. A mold flask consisting of an integral casting in the form of a rectangular frame, flanges spaced apart extending along each side member of the frame, webs connecting the outer edges of the flanges of each side member intermediate the ends thereof, flanges extending across the ends and around the corners of said frame and disposed in a different plane from said first mentioned flanges, said end flanges having downwardly facing sockets at the corners of said frame for cooperation with mold sustaining means.

14. A mold flask consisting of a frame having downwardly opening sockets at its ends for the reception of mold sustaining means,

guide walls adjacent said sockets for directing said means into the sockets, and aligning means carried by said mold flask whereby a plurality of molds may be stacked and supported by a single mold sustaining means.

15. A mold flask consisting of a frame having downwardly opening sockets at its ends for the reception of mold sustaining means, guide walls adjacent said sockets for directing said means into the sockets, means for reinforcing said mold flasks, and aligning means carried by said mold flasks whereby a plurality of molds may be stacked and supported by a single mold sustaining means.

15. 16. A mold flask consisting of a frame having downwardly opening sockets at its ends for the reception of mold sustaining means, guide walls adjacent said sockets for directing said means into said sockets, means for reinforcing said mold flask, and means independent of said sockets for aligning said mold flask with similar flasks whereby a plurality of mold flasks may be stacked and held by a single sustaining means.

25. In testimony whereof, I hereunto affix my signature.
